INVENTOR

BY *James J. Sheehan & Co.*
ATTORNEYS

UNITED STATES PATENT OFFICE.

CHARLES A. PROULX, OF WOONSOCKET, RHODE ISLAND.

SPINDLE.

Application filed July 6, 1921. Serial No. 482,738.

To all whom it may concern:

Be it known that I, CHARLES A. PROULX, a citizen of the United States, residing at Woonsocket, in the county of Providence and State of Rhode Island, have invented 5 new and useful Improvements in Spindles, of which the following is a specification.

My present invention pertains to spindles such for instance as are employed to support 10 a bobbin or other yarn holding device on spinning machines and the like, in which the spindle remains stationary and the bobbin rotates about the same incident to the unwinding of the yarn from the bobbin. 15 The object of the invention is not only to centralize the spool or bobbin about the supporting spindle with but a slight amount of friction, but to overcome the objection of the flyings of the yarn from clogging under 20 the base of the spindle and thereby prevent rotation of the bobbin.

The invention in all of its details will be 25 fully understood from the following description and claims, when the same are read in connection with the drawings, accompanying and forming part of this specification, in which:

Figure 1 is a side elevation of the spindle and bobbin as properly positioned thereon.

Figure 2 is a longitudinal sectional view 30 of the spindle.

Figure 3 is a slight modification of the spindle construction shown in Figures 1 and 2.

Similar numerals of reference designate 35 corresponding parts in Figures 1 and 2 of the drawings, which figures I will describe first.

The stationary spindle 1 is slightly decreased in diameter at its lower end as indicated by 2 and the said lower end 2 is adapted 40 to seat on the opening of the board or frame 3 as illustrated.

Secured to and adapted to remain fixed 45 with respect to the spindle is the base portion 5 that is provided with the integral collar portion 4, and surrounding the base 5 and also a portion of the spindle 1 and adapted to revolve with respect to the base 50 and spindle is the casing 7.

The base 5 is so constructed at its upper end that a ball race is provided for the bearings 6 between the casing 7.

At its upper end the spindle is provided 55 with a member 9 that is decreased in size at its lower end 10 whereby it may be forced

into the upper end of the spindle, adapted to seat between the shoulder at the lower surface of the member 9 and the upper end of the spindle is a ring 8. This ring is 60 for the purpose of diminishing friction between the bobbin 11 and the spindle and as will be manifest the said ring is adapted to revolve with respect to the spindle, and hence the bobbin will be centralized at all 65 times.

At this point I would have it distinctly understood that I do not wish to confine myself to the exact construction of member 9 as said member may be constructed in any 70 manner which fairly falls within the scope of my claims, as its sole purpose is to confine the ring 8 on the spindle 1.

In Figure 3 I have shown the modified form of construction of the base 5^a having 75 the collar 4^a and the revoluble member 7^a together with the bearings 6^a. The construction is practically the same as that shown in Figures 1 and 2, with the exception that the top of the base 5^a is of a slightly different 80 configuration.

Because of the construction of the device the base portion is lifted slightly above the board 3 and hence the liability of flyings from the yarn gathering under the base and 85 the board to the extent that said flyings impede the proper rotation of the bobbin is effectually precluded, and the stopping of the bobbin or the breaking of the yarn from such cause is practically overcome. 90

The construction will also assure the even retention of the bobbin in one position with respect to the spindle 1, and due to the construction of the ring 8 and casing 7, all friction will be removed between the spindle 95 and bobbin.

The device illustrated and described is simple in construction and comprises no delicate parts such as are liable to become inoperative after a short period of use and 100 the construction will obviously overcome many of the disadvantages attributable to spindles now in use.

Having described my invention, what I claim and desire to secure by Letters-Patent, is:—

1. In a device for the purpose set forth, the combination of a spindle slightly decreased in diameter at its lower end, a casing surrounding the spindle and secured thereto, a ferrule mounted in the upper end of the spindle, a ring arranged on the spindle

- and adapted to rotate with respect to the spindle and ferrule, a revolute core arranged in the casing and having an integral collar whereby the spindle is elevated and 5 anti-friction means arranged between the core and casing; said casing being so constructed and arranged to prevent foreign matter from gaining access to the anti-friction means.
- 10 2. In means for the purpose set forth, the combination of a spindle, a ring arranged on one end of the spindle, a casing secured to the opposite end of the spindle, a revolute member arranged within the casing and having a lower depending portion for elevating the spindle, and anti-friction means interposed between the casing and revolute member and adapted to prevent yarn from impeding rotation of the revolute member.
- 15 3. In a spindle, having a lower end of decreased circumference, the combination of a casing arranged in the decreased portion of the spindle, a removable member arranged adjacent the spindle within the casing and adapted to be rotated independently of the 20 spindle, and having an integral portion for elevating the spindle, anti-friction means interposed between the revolute member and the spindle and means arranged on the upper end of the spindle for centering a 25 bobbin thereon.
- 30 In testimony whereof I have hereunto set my hand in presence of two subscribing witnesses.

CHARLES A. PROULX.
